UNITED STATES PATENT OFFICE.

OTIS A. MYGATT, OF NEW YORK, N. Y.

COMPOUND SHADE-REFLECTOR OF GLASS.

1,019,179.

Specification of Letters Patent.

Patented Mar. 5, 1912.

Application filed July 14, 1905. Serial No. 269,715.

To all whom it may concern:

Be it known that I, OTIS A. MYGATT, citizen of the United States, residing at New York, in the county of New York and State of New York, have invented certain new and useful Improvements in Compound Shade-Reflectors of Glass, of which the following is a specification, reference being had therein to the accompanying drawing.

10 This invention relates to shade-reflectors (for artificial lights) composed of glass, known as transparent glass, although sometimes slightly tinted.

The object of the invention is to produce 15 a reflector and shade combined, in which a definite amount of light can be permitted to pass through the shade-reflector, and a definite amount can be reflected back, and, if desirable, the quality or direction, or both, 20 of light rays may be changed by passing through the shade, as well as the quality of the reflected rays which do not pass through the glass of the reflector, but are reflected thereby. The transmission is obtained 25 by transmitting, or transmitting and directing, surfaces placed between the longitudinal sides of the reflecting prisms.

Figure 1 is a side elevation of a shade-reflector involving the principles of my 30 present invention. Fig. 2 is a top plan of the same. Fig. 3 is a side elevation of a modification.

In Fig. 1, A indicates a reflector of common form. B, B indicate external reflecting 35 prisms. As shown, these prisms extend vertically or radially with reference to the body of the reflector. Between reflecting prisms B there are plane surfaces C, which permit the light rays to pass through the 40 glass reflector. From such a construction it will be apparent that nearly all the light rays from a lamp within reflector A which encounter the prisms B will be reflected back and out the open mouth of the reflector, 45 while the rays which encounter plane surfaces C will pass through and out without diversion. (Surfaces C may be slightly convex or concave.)

Frequently the rays which pass through 50 at C are too brilliant for comfortable illumination. Therefore these plane (or slightly convex or concave) faces may be etched or frosted, as at C', this etching or frosting having the effect of softening and diffusing 55 the light rays transmitted, but not of directing the rays in any particular direction.

Should it be desirable to direct a large proportion of the transmitted light rays in a determined direction, instead of employing the frosted surfaces C', I may employ light-refracting or directing ribs or prisms C², arranged horizontally on the body, between the longitudinal sides of the reflecting prisms B, as in Fig. 3. The effect of such light-directing ribs or prisms is to direct the 60 majority of the light rays which reach them in the direction determined by the form of the prismatic surfaces, as explained in my reissued patent aforesaid.

The light which passes through the shade-reflector between the reflecting prisms may be directed either upward or downward by proper and known construction of the prisms C², or may be diffused or softened by the frosted surface C', or may be merely transmitted through the plane surface C, and this direction, transmission, or diffusion may vary with different parts of the surface of the same shade reflector.

A definite quantity of light may be transmitted and a definite quantity reflected, a definite proportion may be distributed in directions other than the natural direction of the light rays, and a highly decorative article may at the same time be produced.

For cheapness of construction and perfection of finish my shade-reflectors are preferably of one piece of pressed transparent glass. Frosted surfaces are afterward etched or ground on. But all processes usual in this 90 art may be employed in the production of shade-reflectors according to my invention.

The shade-reflectors are not necessarily frusto-conical, but are of all the forms usual in this art. By reflecting prisms, I mean 95 prisms whose sides make angles of substantially 45° with incident light rays and have an apex angle of substantially 90°.

What I claim is:

1. A glass shade-reflector having an open 100 mouth, provided with reflecting prisms disposed longitudinally and adapted to reflect light rays back and out of the open mouth of the reflector, and ribs interposed between the longitudinal sides of said prisms.

2. A shade-reflector having an open mouth, provided with radial reflecting prisms for reflecting light rays back into and out of the open mouth of the reflector, and light transmitting ribs interposed between the longitudinal sides of the prisms.

3. A glass shade-reflector having an open

2
mouth, provided with radial reflecting prisms for reflecting light rays back into and out of the open mouth of the reflector, and light transmitting surfaces interposed between the longitudinal sides of said prisms.

4. A glass shade-reflector having an open mouth, provided with radial reflecting prisms for reflecting light rays back into and out of the open mouth of the reflector, and circumferential ribs interposed between the longitudinal sides and substantially at right angles to said prisms.

5. A glass shade-reflector having an open

mouth, provided with radial reflecting prisms for reflecting light rays back into and out of the open mouth of the reflector, and light directing transverse surfaces interposed between the longitudinal sides of the prisms.

In testimony whereof I affix my signature 20
in presence of two witnesses.

OTIS A. MYGATT.
